UNITED STATES PATENT OFFICE.

JOHN RIDDELL, OF SCHENECTADY, NEW YORK, ASSIGNOR TO GENERAL ELECTRIC COMPANY, A CORPORATION OF NEW YORK.

MACHINE FOR DRILLING PORCELAIN.

1,022,874.

Specification of Letters Patent.

Patented Apr. 9, 1912.

Application filed August 8, 1908. Serial No. 447,563.

To all whom it may concern:

Be it known that I, JOHN RIDDELL, a citizen of the United States, residing at Schenectady, county of Schenectady, State of New York, have invented certain new and useful Improvements in Machines for Drilling Porcelain.

This invention relates to the art of making porcelain ware, and especially the insulators used to separate sections of trolley lines, or to support transmission lines carrying high potential. These link strain insulators consist of a solid disk of porcelain having a rim provided with double flanges to afford a long creepage surface between line portions of the circuit, and insuring the sheltering of some part of said surface from the rain. The center of the disk is thickened, forming a body to contain two inter-linked U-shaped holes, one in each side of the disk, through which the cables or guy wires are threaded. These holes must be drilled in the green porcelain, and the present invention is a machine for doing this drilling. Inasmuch as the holes are U-shaped or, more properly, semicircular, the machine is designed to drill one half of a hole at each operation, the halves meeting in the body of the disk. The machine also cuts away the stock between the hole and the thinner portion of the disk, to facilitate the insertion of the wire or cable. It also rounds off the body between the ends of the hole. The insulator is mounted in a holder which is capable of rotary and rocking movements, while the drill is so mounted that its angle of approach to the work can be altered. The drill is both rotatable and reciprocable in any angular position to which it can be adjusted.

In the accompanying drawings, Figure 1 is a perspective view of a machine embodying my invention; Fig. 2 is a plan view of the same, with the drill and work-holder removed; Fig. 3 is a side elevation, partly in section, of the drill and its motor; Fig. 4 is a cross section on the line 4—4, Fig. 3; Fig. 5 is an elevation of the work-holder holding an insulator; Fig. 6 is a cross section of the completed insulator; and Figs. 7, 8 and 9 are sectional plan views showing the operation of the machine.

On a standard 1 is secured a bed-plate or table 2 containing ways 3 concentric with a pivot 4 on which is pivoted a carriage 5 en-

gaging with the ways and capable of lateral angular movement over said table. The carriage can be locked in three positions of angular adjustment, preferably by means of a spring catch 6 engaging with holes 7 in the table. A drill 8 is mounted on the table, with means for rotating it, preferably an electric motor 9 which drives the drill through gearing 10, 11. The hub 12 of the gear 11 is rather long, and splined therein is the drill holder 13. A sleeve 14, located between collars 15 on said holder, is provided with rack-teeth 16 which mesh with a gear wheel 17 journaled in lugs 18 on the frame 19 carrying the drill; said frame being conveniently mounted on the frame of the motor. The gear-wheel 17 can be rotated by a crank 20 which has a spring latch 21 engaging notches in a quadrant 22 on the drill-frame. The latch is preferably operated by a plunger 23 in the crank, having a thumb-piece 24 and a wedge 25 to lift the latch. The cutting element of the drill is a small disk 26 of hardened steel rotatably journaled in an axial slot in the end of the drill-shank 27. The axis of the drill is in the vertical plane of the pivot 4, and the shank 27 extends beyond said pivot at all times.

The work-holder consists of a circular frame 28 having two sets of diametrically opposite trunnions 29, 30 arranged at right angles. Midway between the trunnions of the two sets are laterally projecting arms 31 upon which are supported two sheet metal pans 32. Each pan is conformed to one side of an insulator 33 and has a central opening 34 with oppositely arranged radial slots 35; the slots in one pan being at right angles to those in the other. One pan is fastened to its arms 31 by strips 36. Similar strips on the other pan are detachably secured to the arms 31 by catches 37. The frame 28 is held in a yoke 38, one pair of trunnions being received in open bearings 39 in the upper ends of the arms of said yoke, while the lowermost trunnion of the other pair enters a socket in the crotch of the yoke and thus holds the frame steady. The yoke extends up from a base 40 which is swiveled on a stud 41 rising from a carrier 42 mounted on a support 43 rigidly secured to the table 2 adjacent to the pivot 4. The swivel joint can be locked by a set screw 44. The carrier has two downwardly

projecting pivot pins 45 45' in the rear of the holder which engage in slots 46 46' in the support 43, each slot being curved on an arc struck from the other pivot pin. 5 Locking devices, such as the removable transverse bolts 47 47', keep the pivot pins normally at the inner ends of said slots.

The operation is as follows: The removable pan 32 is taken off and an insulator 33 10 is placed against the other pan and secured by replacing the removable pan. The frame 28 is inserted in the yoke 38 in the position shown in Figs. 5 and 6. The drill carriage 5 is adjusted in its central position, with the 15 shank 27 of the drill in line with the center of the insulator, and the rotating cutter 26 is moved up against the surface of the work. The yoke 38 is then turned by hand on its pivot stud 41, whose axis is in line with the 20 center of the semi-circular hole 48 to be cut in the insulator and at right angles to the axis of the drill shank. This operation (Fig. 7) cuts a semicircular groove in the face of the central body of the insulator, concentric 25 with the center of the hole to be cut. The ends of this groove enter the body, leaving a thin wall 49, as shown at the right side of the insulator in Fig. 7. To remove this wall, the drill carriage is set over, say to the 30 left, swinging the cutter to the right, as shown in Fig. 8, so that its shank is tangent to the inner wall of the groove already cut. The bolt 47 holding the opposite side of the carrier is pulled out, and the carrier is 35 rocked back and forth on its right hand pivot pin 45', and the cutter is advanced until it reaches the position indicated in Fig. 8. This causes the cutter to form and smooth off the curved surface 50. The carrier is now brought back to its normal position, and the bolt 47 replaced. The yoke 38 40 can now be swiveled on its stud, causing the cutter to drill the right-hand half of the semi-circular hole 48, as shown in Fig. 9. The radial slots 35 in the pan permit the 45 work-holder to turn without coming in contact with the drill shank. The drill-carriage is now set over to the right, and the smoothing and drilling operations are re-peated on the left-hand side of the insulator, using the left-hand pivot 45. The half-hole thus formed meets the one previously drilled and completes the orifice. The frame 28 is then lifted out of the yoke, faced about, 50 and given a quarter revolution in its own

plane to bring the trunnions 30 into position to enter the bearings 39. All the above-described operations are then repeated on that face of the insulator, resulting in the semi-circular hole 51 interlinking with the hole 48. 60

What I claim as new and desire to secure by Letters Patent of the United States, is:

1. A machine for drilling porcelain, comprising a rotary cutter, a pivoted carriage for said cutter, a work-holder, and means 65 whereby said holder may be rotated on any one of three parallel axes prependicular to the axis of the cutter-shank.

2. A machine for drilling porcelain, comprising a rotary cutter, means for approaching it to the work at different angles, a work holder mounted on a swiveled part, and a carrier for said swiveled part capable of rocking laterally on either of two pivotal 70 points. 75

3. A machine for drilling a semicircular hole in porcelain insulators, comprising a rotary tool, a holder for the insulator, means for pivotally supporting said holder whereby it can be rotated on the axis of the hole 80 to be bored, and means for engaging said pivotal supporting means whereby said holder can be rocked on an axis eccentric to said hole.

4. A machine for drilling a semicircular 85 hole in porcelain insulators, comprising a table having ways, a carriage pivoted on said table and riding on said ways, a motor on said table, a drill mounted on the motor frame and geared to said motor, means for reciprocating said drill, and means for supporting the insulator comprising a work 90 holder, a swiveled part on which said holder is mounted, said part being arranged with its axis perpendicular to the axis of said drill and capable of rocking about either of two other pivotal axes. 95

5. A machine for drilling porcelain insulators, comprising a rotary cutter, a swiveled part, a work holder mounted on said part, 100 a carrier on which said part is swiveled, a support for said carrier provided with slots, and pivot pins on said carrier engaging said slots.

In witness whereof, I have hereunto set 105 my hand this 7th day of August, 1908.

JOHN RIDDELL.
